Charles H. Morris ATTORNEY

UNITED STATES PATENT OFFICE.

MOÏNA MICHAEL, OF NEW YORK, N. Y., ASSIGNOR OF ONE-HALF TO LEE KEEDICK, OF NEW YORK, N. Y., AND ONE-HALF TO OTHO L. FERRIS, OF PORTLAND, OREGON.

DESIGN FOR A FLAG OR BANNER.

53,080.

Specification for Design.

Patented Mar. 11, 1919.

Application filed December 26, 1918. Serial No. 268,393. Term of patent 14 years.

To all whom it may concern:

Be it known that I, MOÏNA MICHAEL, residing at New York, county and State of New York, have invented a certain new, original, and ornamental Design for a Flag or Banner, of which the following is a specification, reference being had to the accompanying drawing, forming part thereof.

The figure is an elevational view of a flag or banner, showing my new design.

I claim:

The ornamental design for a flag or banner, as shown.

MOÏNA MICHAEL.

Witnesses:

CHARLES H. WILSON,
LEE KEEDICK.
